UNITED STATES PATENT OFFICE.

WILLIAM R. BALLARD, OF HAUBSTADT, INDIANA.

SASH FASTENER.

Application filed January 25, 1922. Serial No. 531,697.

To all whom it may concern:

Be it known that I, WILLIAM R. BALLARD, a citizen of the United States, residing at Haubstadt, in the county of Gibson and 5 State of Indiana, have invented a new and useful Improvement in Sash Fasteners, of which the following is a specification.

This invention relates to sash fasteners.

The object is to provide a fastener for 10 window sashes which will effectually lock the upper sash from being lowered or the lower sash from being raised until the parts are manually released, when these movements of the sashes may be accomplished and 15 the coacting parts of the fastener are in a position to automatically lock again, when the sashes are moved to closed position to prevent their movement until again released.

Another object is to improve the construction of sash fasteners by the elimination of 20 friction in the movement of the locking lever through the medium of a ball bearing, which not only facilitates said movement but provides for a silent movement of said lever. 25 the latter being provided with an extension projecting from the casing of the lock for the attachment of a cord or the like by means of which the fastener may be released for action in permitting the movement of 30 either of the sashes from a distance, this being especially advantageous where the lock is used on windows of considerable height.

A full and complete understanding of the 35 invention may be obtained from a consideration of the following detailed description, taken in connection with the accompanying drawing forming a part of this specification, it being understood that while the drawing 40 shows a practical form of the invention, the latter is not confined to strict conformity therewith, but may be changed or modified, so long as such changes or modifications mark no material departure from the salient 45 features of the invention, as specifically pointed out in the appended claims.

In the drawing, in which similar reference characters designate corresponding parts throughout the several figures:

50 Figure 1 is a perspective view of a portion of the meeting rails of window sashes having the members of the sash fastener attached thereto and showing the same in locked position.

55 Figure 2 is a detail perspective view of the locking member of the fastener, the cas-

ing or housing being partly broken away to better disclose the locking lever and the trigger;

Figure 3 is a transverse sectional view 60 through the coacting members of the fastener and the respective rails on which they are mounted, the parts being in position to permit the movement of the sashes;

Figure 4 is a similar view showing the 65 trigger in position to hold the locking lever back from engagement with the keeper;

Figure 5 is an inverted plan of the locking member, the casing or housing being 70 partly broken away.

In the drawing there is illustrated the upper cross bar or rail 1 of the lower sash of a window, and the lower rail 2 of the upper sash thereof, which are shown in Figure 1 in the usual meeting relation when the sashes 75 are closed. Mounted on the upper face of the rail 1 is an elongated rectangular housing 3, comprising a base plate 4 having extensions or ears 5 at each end, suitably apertured for the reception of fastening 80 screws 6, which have their heads countersunk in the ears and serve to hold the housing of the locking mechanism at a point substantially at the center of the rail as is usual.

85 The front wall 7 of the housing, or that wall facing towards the interior of the room, is imperforate while the opposite wall, or that directed towards the adjacent lower rail 2 of the upper sash, is provided with the 90 opening 8 extending from end to end thereof, and one of the end walls 9 of the housing is provided with the opening 10 for a purpose to be explained.

The top or cover 11 of the housing may 95 consist of a plate co-extensive with the housing and having its corners secured to the corners of the housing as by screws or rivets, after certain parts to be described are properly mounted therein. The cover 11 is provided at its center with a raised enlargement or dome 12 extending transversely thereof, and provided with a transverse slot or opening 13 extending towards the rear wall of the housing and communicating with 100 the opening 8 therein.

A keeper 14 is carried by the lower sash rail 2 of the upper sash, and comprises a plate of equal length and height to the housing 3, said plate 14 having a slot 15 extending throughout the major portion of its length and having a reduced attaching por-

tion 16 along its lower edge, which is countersunk into the front face of the rail 2 so that the front face of the keeper is flush with the front face of the rail throughout its length, the attaching portion 16 being suitably apertured for the reception of countersunk heads of screws shown in dotted lines in Figures 3 and 4. The upper edge of the keeper has its front corner rounded as at 17.

10 Mounted within the housing is a locking lever 19 which has its inner enlarged end pivoted upon a vertically disposed pivot pin 20 located near the imperforate end wall 9, and the said lever is gradually reduced in width towards the other end thereof where it terminates in a finger 21, which extends through the opening or slot 10 in the other end wall 9 and is adapted to have the end of a cord 22 or chain attached thereto for the purpose of operating the said lever from a distance. The rear face or edge of the locking lever is adapted to normally lie flush with the rear edge of the base plate 4 of the housing, as clearly shown 25 in Figure 2 of the drawing, and the said lever is provided at an intermediate point, in alinement with the slot 13 of the cover 11 with a recess 23 into which is adapted to project the lower end of a locking dog or trigger 24.

30 The lever 19 is further provided, adjacent to the recess, with tongue 25 formed integrally therewith having its lower edge beveled as at 26 and adapted to normally 35 extend beyond the rear face of the housing and into the slot 15 of the keeper 14, under the action of a metal spring 27 resting upon the upper face of the base plate 4 of the housing and confined within a cut-out portion 28 provided in the under face of the lever 19 for the purpose. The spring 27 consists of a length of resilient spring steel 40 bent at an intermediate point to provide spaced opposed arms to bear respectively 45 against the inner face of the front imperforate wall 7 of the housing and against the opposed wall of the lever 19 formed by the cut-out portion thereof, as clearly shown 50 in Figure 5 of the drawing, the extent of rearward movement of the lever 19 being limited by the projecting finger 21 thereof coming into contact with the rear end of the slot or opening 10 formed in the end wall 9. The lever is thus held in position 55 under tension of the spring 27, with the tongue 25 projecting into the slot 15 of the keeper, which will prevent the upward movement of the lower sash until the locking lever 19 is caused to move away from 60 the keeper by a pull on the cord or chain, or otherwise engaging the projecting finger 21 of the lever, at which time the pressure on the said spring is increased.

65 The locking dog or trigger 24 consists of a metallic block having its outer exposed

face conforming with and lying flush with the upper surface of the dome 12, and snugly fitting the slot 13 therein, a pivot pin 29 passing horizontally through the dog or trigger near its rear face, and having its ends carried by the adjacent walls of the slot 13 and serving as a fulcrum for the dog for the same to rock about by gravity.

70 The dog or trigger 24 has its lower front portion cut away to provide a horizontal abutment shoulder 30 adapted to normally rest upon the upper face of the locking lever 19 as shown in Figure 3, while the forward end of said shoulder is provided with another cut-out; thus providing a second shoulder 31 which is adapted to rest upon the upper face of the lever when the latter is moved forwardly by the string 22, or otherwise, and to hold the said lever in such position by reason of the fact that the 80 abutting wall 32 formed by said second cut-out is bearing against the rear wall of the recess 23 in the lever 19 and holding the same against movement, as clearly shown in Figure 4 of the drawing.

90 With the rails 1 and 2 in parallel relation to each other, when the window is closed, as shown in Figure 1, the spring 27 forces the locking lever 19 rearwardly until the finger 21 strikes the rear end of the slot 10 in the end wall 9, at which time the tongue 25 is projected into the slot 15 of the keeper 14 carried by the lower rail 2 of the upper sash, and by reason of this fact neither of the sashes can be moved in an upwardly or 95 downwardly direction. The rear portion of the dog or trigger 24, which is reduced by reason of the cut-out forming the shoulder 30, is extended rearwardly at its lower end to form a toe 33, having its upper face 100 curved as at 34, and said toe is confined within the housing between the walls of the slot 23 with the shoulder 30 of the dog or trigger resting upon the upper face of the locking lever through gravity by reason of 105 the rearward position of the pivot pin 29. If now it is desired to raise the lower sash or lower the upper sash to open the window, the string or chain 22 is pulled, or the lever 110 115 120 125 130 135 140 145 150 155 160 165 170 175 180 185 shoulder 30 into alignment with the upper face of the lever 19, when the latter is immediately projected rearwardly again by means of the expansive force of the spring 27, and the tongue 25 caused to lie in the path of the keeper but above and free of the same, to be brought subsequently into contact with the upper rounded edge 17 thereof, when the sashes are closed again, 10 such contact causing the lever to recede to permit the tongue to pass the keeper bar and to be immediately projected again by the spring to lock the two sashes together. It will thus be seen that to open the window, 15 it is necessary to manually operate the locking lever, and that the trigger or dog automatically acts to hold the lever in retracted position, and that when the sashes are opened, the upper rounded face of the toe 20 33 serves to elevate the active end of the trigger so that the lever may spring into locking position again to automatically lock with the keeper, when the sashes are again closed.

25 Mounted within a suitable recess in the upper face of the lever 19 substantially at the base of the tongue 25, is an anti-friction ball 35 which provides for the easy and noiseless movement of the said lever, the 30 said ball bearing against the under side of the cap or cover 11.

From the foregoing it will be seen that a simple and cheaply manufactured sash fastener has been provided, which may be 35 easily installed in position on the sashes of a window, and that the same effectually prevents closing the sashes without locking the same, as the moment the coacting locking members pass each other in an opening 40 movement, the said parts are set to automatically lock when the sashes are again closed.

While I have described my invention as a sash fastener, the device has possibilities of 45 use outside of the meeting rails of sashes together and may be employed in analogous relations in detachably securing two movable parts or members.

What is claimed is:

50 1. In a fastening device, a housing adapted to be secured to one movable member, said housing having an opening in its side wall, a horizontally swinging locking lever arranged within the housing and pivoted thereto, said locking lever having a tongue, a spring within the housing bearing against the lever to project the tongue through said side opening, a trigger within the housing for engaging the lever when the latter is retracted, said trigger having a part projecting from the housing when in engagement with the lever, and a keeper carried by another member to be engaged by the tongue of the locking lever, said keeper being adapted to engage the projecting part of the

trigger, when said members are moved relatively to each other, so as to release the trigger from its engagement with the lever.

2. In a fastening device, the combination of a housing adapted to be secured to one member, said housing having an opening in its side wall, a horizontally swinging locking lever pivoted within the housing and having a tongue, a spring within the housing adapted to project the tongue of the lever through the side opening, a trigger pivoted above the lever and adapted to engage the latter by gravity when the lever is retracted against the tension of the spring, and a keeper carried by another member adapted to be engaged by the tongue of the lever to prevent relative movement of said members, said keeper being adapted to actuate the trigger upon relative movement of said parts to disengage the trigger from the lever.

3. A fastening device comprising a housing having an opening in one side and one end wall, a horizontally swinging locking lever pivoted in the housing and having a tongue extending through the side opening and a finger projecting through the end opening, a spring within the casing operating against the lever to project the tongue from the housing, a trigger pivoted to the housing above the lever and adapted to engage by gravity an edge of the lever when the latter is retracted, and a keeper to be engaged by the tongue of the locking lever, said keeper being adapted to actuate the trigger to disengage the trigger from its engagement with the lever.

4. In a sash fastener, the combination of a housing adapted to be secured to the top rail of a lower sash, said housing having an opening in a side wall and an opening in an end wall, a horizontal swinging locking lever arranged within the housing and pivoted at one end remote from the open end of the housing, and having a tongue adapted to be extended through the side opening and a finger extending through the end opening, a spring for the lever which normally tends to force the tongue outwardly through the side opening, a horizontally pivoted trigger adapted to engage by gravity with an edge of the lever when the latter is retracted against the tension of the spring, and a loop-shaped keeper carried by the lower rail of the upper sash to be engaged by the tongue of the locking lever so as to prevent movement of the sashes, said keeper being adapted to actuate the trigger when one of the sashes is moved to disengage the trigger from the lever.

5. A sash fastener comprising a lock housing adapted to be secured to the top rail of a lower sash, said housing having an elongated opening in its rear wall, and an opening in one end wall, a horizontally swinging

locking lever pivoted at its inner end within the housing and having a tongue extending through the rear elongated opening, and a finger extending through the end opening for the attachment of a pull cord or chain to swing the lever, a spring within the housing and adapted to force the movable end of the lever in a rearward direction to project the tongue, a horizontally pivoted trigger or dog having a toe and mounted within the cover of the housing above the locking lever to swing transversely thereof and having a vertically disposed shoulder adapted to engage by gravity with the edge

of the lever when the latter is retracted into the housing to hold the same, and a loop-shaped keeper carried by the lower rail of the upper sash to be engaged by the tongue of the locking lever to prevent movement of the sashes and adapted to actuate the trigger when the sashes are moved to remove the shoulder of the trigger from its engagement with the lever to set the latter for automatic locking.

In testimony that I claim the foregoing as my own, I have hereto affixed my signature.

WILLIAM R. BALLARD.
